DESIGN FOR A VASE OR SIMILAR ARTICLE

Ted Mehrer, New York, N. Y., assignor to Verlys of America, Inc., New York, N. Y., a corporation of New York

Application November 16, 1939, Serial No. 88,311

Term of patent 7 years

To all whom it may concern:

Be it known that I, Ted Mehrer, a citizen of the United States of America and a resident of New York city, New York, have invented a new, original, and ornamental Design for a Vase or Similar Article, of which the following is a specification, reference being had to the accompanying drawing, forming a part thereof.

The figure is a perspective view of a vase or similar article showing my new design, the ornamentation on the three front panels is repeated on panels not shown.

I claim:

The ornamental design for a vase or similar article, as shown and described.

TED MEHRER.
